UNITED STATES PATENT OFFICE.

JOSEPH A. MALLETT, OF WORCESTER, MASSACHUSETTS.

DESIGN FOR A WRENCH.

57,847.

Specification for Design.

Patented May 10, 1921.

Application filed September 18, 1920. Serial No. 411,331. Term of patent 3½ years.

To all whom it may concern:

Be it known that I, JOSEPH A. MALLETT, a citizen of the United States, residing at Worcester, in the county of Worcester and State of Massachusetts, have invented a new and original and ornamental Design for a Wrench, of which the following is a specification, reference being had to the accompanying drawing, forming a part of this

specification, in which the figure is a perspective view of a wrench showing my new design.

I claim:—

The ornamental design for a wrench as shown.

In testimony whereof I have hereunto affixed my signature.

JOSEPH A. MALLETT.
